CLAIM

The ornamental design for an electric bicycle, as shown and described.

DESCRIPTION

FIG. 1 is a top, front and left side perspective view of an electric bicycle showing my new design;

FIG. 2 is a top, rear and right side perspective view of thereof;

FIG. 3 is a left side elevational view thereof;

FIG. 4 is a right side elevational view thereof;

FIG. 5 is a rear elevational view of thereof;

FIG. 6 is a front elevational view of thereof;

FIG. 7 is a top plan view thereof;

FIG. 8 is a bottom plan view thereof;

FIG. 9 is an enlarged view of portion 9 in FIG. 5;

FIG. 10 is an enlarged view of portion 10 in FIG. 6;

FIG. 11 is an enlarged view of portion 11 in FIG. 8; and,

FIG. 12 is an enlarged view of portion 12 in FIG. 8.

1 Claim, 12 Drawing Sheets
